CLAIM

The ornamental design for an air freshener device, as shown and described.

DESCRIPTION

FIG. 1 is a right front perspective view of a first embodiment of an air freshener device showing the invention;

FIG. 2 is a left bottom perspective view of the air freshener device of FIG. 1;

FIG. 3 is a top plan view of the air freshener device of FIG. 1;

FIG. 4 is a bottom plan view of the air freshener device of FIG. 1 in which an optional stabilizing rib is shown in phantom outline;

FIG. 5 is a left side elevational view of the air freshener device of FIG. 1 in which the stabilizing rib is shown in phantom outline, wherein the right side elevational view is a mirror image thereof;

FIG. 6 is a rear elevational view of the air freshener device of FIG. 1;

FIG. 7 is a front elevational view of the air freshener device of FIG. 1;

FIG. 8 is a left front perspective view of the air freshener device of FIG. 1 installed within a motor vehicle air conditioning vent, which vent is in phantom outline; and,

FIG. 9 is a left front perspective view of a second embodiment of an air freshener device showing the invention installed within a motor vehicle air conditioning vent, which is in phantom outline, wherein said figure further shows an optional logo or commercial indicia on a front surface of said device in phantom outline; wherein the top plan view, bottom plan view, left side elevational view, right side elevational view, front elevational view and rear elevational view are otherwise the same as shown with respect to the first embodiment of the air freshener device shown in FIGS. 1-8.

The elements shown in phantom lines are for illustrative purposes only and form no part of the claimed invention.
